EXHAUST SLEEVE FOR DEEP WELL AIR PUMPS

Filed Oct. 2, 1924

2 Sheets-Sheet 2

UNITED STATES PATENT OFFICE.

RALPH H. TUCKER, OF LOS ANGELES, CALIFORNIA.

EXHAUST SLEEVE FOR DEEP-WELL AIR PUMPS.

Application filed October 2, 1924. Serial No. 741,242.

An object is to provide an exhaust sleeve for deep well air pumps of the type shown, claimed and described in my companion application for air lift pumps, filed June 9, 5 1924, Serial No. 718,794, which has matured into Patent No. 1,588,561, issued June 15, 1926.

In the former application the air is exhausted into the oil tubing string and this 10 string may be of considerable length, and when the pump is operating the tubing string is necessarily filled with oil and the weight of this oil produces a back pressure against the exhaust of the pump.

15 While the oil tubing string may be of considerable length the oil around the tubing string may be low and it is the object of this invention to discharge the exhaust outwardly through the pump mechanism to the oil within 20 the well casing around the pump mechanism, thereby reducing the back pressure on the exhaust.

Another objection to discharging the exhaust air into the oil tubing string is that the 25 passage of air upwardly through the oil tends to form an emulsion between the oil and any water contained in the oil, and furthermore there is no easy way of getting rid of the air, that is of separating the air from the 30 oil at the top of the well, and it is the object of this invention to overcome these objections.

Other objects and advantages will appear from the drawings and specification.

35 The drawings illustrate the complete pump with the exhaust sleeve in position for use in accordance with the principles of my present invention.

Figure 1 is a vertical diametrical section 40 of a well, a well casing, an air driven pump, and the exhaust sleeve applied to the pump.

Fig. 2 is an enlarged fragmentary sectional detail of the pump mechanism from the piston cylinder upwardly to the exhaust 45 ports into the open well.

Fig. 3 is a cross sectional detail on the lines 3—3 of Figs. 1 and 2 and looking downwardly as indicated by the arrows.

Fig. 4 is a cross section on the lines 4—4 50 of Figs. 1 and 2 and looking downwardly as indicated by the arrows.

Fig. 5 is a fragmentary vertical sectional detail on the line 5—5 of Fig. 4 and looking in the direction indicated by the arrows.

Fig. 6 is a fragmentary vertical sectional detail on the line 6—6 of Fig. 4 and looking in the direction indicated by the arrows.

The details of construction and operation shown in the drawings are as follows:

The well hole 1 and the well casing 2 may 60 be any of the usual constructions and conditions.

The oil tubing string 3 may be of any desired size that will pass freely into the well casing 2. A coupling 4 is placed upon the lower end of the oil well string 3 and has a beveled internal seat 5 within the vertical plane of the chamber 6 in the oil well string. A pump cylinder housing 7 is screwed upwardly into the coupling 4 and has a perforated cap 8 upon its lower end. The air pipe 9 is a string of practically the same length as the oil tubing string 3 and may be of any desired size that will pass freely into the oil tubing string 3. A spring seat 10 fits against the lower end of the air pipe 9. An expansive coil spring 11 fits upwardly against the spring seat 10. A hollow plunger buffer 12 fits against the spring 11 and has radial slots 13 formed from its lower end and producing 70 teeth 14. A nipple 15 is screwed upon the lower end of the air pipe 9 and has a shoulder 16 engaging the spring seat 10. A spring housing 17 extends downwardly from the nipple 15 and has a shoulder 18 against which 75 the flange 19 of the plunger 12 engages so as to support the plunger and spring.

A cylinder 20 extends downwardly from the housing 17 and has a spider 21 with a beveled finished outer face fitting upon the seat 90 5 to support the pump mechanism and the air pipe 9. A piston cylinder supporting member 22 is screwed upon the spider 21, there being ports 23 leading through the spider from the cylinder chamber 24. A piston cylinder head 25 is screwed into the lower end of the supporting member 22 and a piston cylinder 26 is screwed upon the head 25 against the member 22. A plug 27 is screwed into the lower end of the cylinder 26. A chamber 28 is formed from the upper face of the plug 27. An expansive spring 29 is mounted in the chamber. A buffer 30 is mounted upon the spring 29 and has a flange 31 extending from its lower part. A ring 32 is screwed into the top of the chamber 28 to engage the flange 31 and limit the upward movement of the buffer under the tension of the spring 29.

Teeth 33 extend upwardly from the buffer 30, the upper ends of the teeth being all on a level.

A piston 34 is slidably mounted in the cylinder 26 and has a hollow stem 35 extending upwardly slidably through the cylinder head 25 and slidably into the cylinder 20. A valve 36 fits slidably in the hollow of the stem 35 and has a head 37 with a flat lower face adapted to fit upon the upper ends of the teeth 33. The head 37 has a beveled upper outer face 38 to fit a beveled valve seat 39 formed in the lower end of the hollow stem 35, so that when the piston 34 is down with the head 37 upon the teeth 33, the head 37 is in engagement with the seat 39 to close the passage around the valve 36 in the stem 35. Ports 40 are formed through the stem 35 above the cylinder head 25. Grooves 41 are formed longitudinally in the periphery of the valve 36 from the head 37 upwardly to points above the ports 40.

In forming the grooves 41, webs 42 are inserted across the upper ends of the grooves 25 with the grooves extending inside of the webs to ports 43 above the webs. The webs 42 form port closures and cover the ports 40 when the air pressure is on to raise the piston 34, and uncover the ports 40 after the piston 34 has been raised and should go down. At this time the grooves 41 and the ports 40 serve as exhaust means to let the air out below the piston 34.

The valve 36 is tubular and when the head 37 is seated, the valve 36 extends above the stem 35 and has a head 44 closing the upper end of a chamber 45 of the valve, and the head has a flange 46 to engage the upper end of the stem 35 and ports 47 below the flange, so that when the piston 34 is down, the head 44 is raised and the air pressure coming down the pipe 9 will pass through the ports 47, through the chamber 45, through the teeth 33 to an expansion chamber 48 between the plug 27 and the piston 34, and the air pressure will raise the piston 34 to drive the oil out of the chamber 49 between the piston 34 and the cylinder head 25.

The details of the exhaust sleeve for deep well air pumps are as follows:

The cylinder head 25 consists of an intake valve base *a* and an outlet valve base *b*. The base *b* has an annular upper portion *c* and the supporting member 22 is screwed down upon the periphery of this upper portion to a shoulder *d*. The lower portion *e* of the base *b* extends downwardly from the shoulder *d*, a surface *f* fitting against the inner face of an annular collar 7' integral with the housing 7. Valve seat openings *g* extend upwardly from the lower face of the portion *e* and exhaust ports *h* extend outwardly from the upper ends of the openings *g* to the exhaust chamber *i* between the supporting member 22 and the cylinder housing 7 above the por-

tion 7'. The portion 7' serves to separate the exhaust chamber *i* from the inlet chamber. Valves *j* have stems *k* extending into seats above the ports *h* and expansive coil springs *l* are placed around the stems *k* between the valves and the tops of the ports *h*. Valve seats *m* are screwed upwardly into the openings *g* against the valves *j*. Recesses are formed in the lower face of the portion *e* and form connecting ports *n* leading the exhaust to the valve seats *m*. A conduit *o* is screwed down into the center of the annular portion *c* and spaced away from the stem 35 to form the exhaust conduit passage *p* leading toward the ports *n*. The central opening through the portion *e* is enlarged to form the extension conduit passage *q* leading from the lower end of the conduit passage *p*, and forming a part of the conduit passage *p*. The ports 40 discharge into the passage *p*.

A coupling sleeve *r* is formed integral with the conduit *o* and fits closely around the lower end of the cylinder 20, there being packing rings *s* recessed into the periphery of the cylinder within the coupling sleeve *r* to make a tight joint.

The inlet base *a* fits slidably around the stem 35 and is screwed upwardly into the base *b* and forms bottoms for the ports *n*. The cylinder 26 is screwed upwardly onto the base *a* against the lower face of the portion *e*.

An annular plate 50 fits upon the head 25 and covers outlet ports 51 and 52 formed through the cylinder head 25.

Bolts 53 have heads 54. Expansion coil springs 55 are mounted upon the bolts against the heads 54. Bores 56 are formed from the upper face of the head 25 and the bolts and springs are inserted into the bores. Spring seats 57 are screwed into the bores against the springs 55. The plate 50 is placed in position with the bolts 53 extending through the plate and nuts 58 are screwed down upon the bolts against the plate.

The tensions of the springs 55 are exerted to hold the plate 50 down to close the outlet ports 51 and 52 and support the load of oil in the oil tubing string 3 and chamber 24 and form outlet check valves so that when the piston 34 moves up, the oil in the chamber 49 will pass through the ports 51 and 52 and upwardly.

A plate 59 fits against the lower face of the head 25 and covers elbow-shaped inlet ports 60 and 61 leading from an inlet oil chamber 62 to the chamber 49. Bolts and springs 63 and 64 hold the plate 59 yielding in position so as to form inlet check valves to hold the pressure in the chamber 49 when the piston 34 is going up, and to let the oil into the chamber 49 when the piston 34 is going down. The oil chamber 62 communicates with the oil in the well casing 2 through the perforated cap 8 so that as fast as the oil is pumped from the chamber 62,

more oil will flow upwardly through the cap 8.

When the piston 34 goes upwardly, the head 44 will strike the buffer 12 and the valve 36 will be moved downwardly in the stem 35, thereby closing the ports 47 and moving the port closures 42 to open the ports 40 and moving the head 37 away from the seat 39, thereby allowing the air in the chamber 48 to pass upwardly through the grooves 41 and through the ports 43 and 40 into the conduit passages *p* and *q*, the ports *n*, the valve seat *m* past the valve *j*, and through the outlet ports *h* to the chamber *i* and upwardly through the ports *t* at the top of the housing 7 and into the open well, that is, the space around the pump mechanism within the well casing.

As soon as the air pressure has been sufficiently exhausted from the chamber 48, the air pressure upon the head 44 will move the stem 35 and the valve 36 downwardly until the head 37 strikes the buffer teeth 33 and continued downward movement of the stem 35 will bring the head 37 into the seat 39, then close the ports 40 and open the ports 47 so that the air pressure will pass downwardly to the chamber 48 and again raise the piston 34. There will be sufficient friction between the stem 35 and the valve 36 to carry the valve with the stem until the valve strikes either the buffer 12 or the buffer 30.

As above stated, the discharge of the exhaust air into the open well greatly reduces the back pressure upon the exhaust and is an easy way of separating the air from the oil. This disposition of the air also avoids the liability of emulsifying the oil and water in the oil string.

The pump mechanism as constructed and operated without the exhaust sleeve is shown, described and claimed in the companion application above cited, and I do not wish to make such claims herein.

Various changes may be made without departing from the spirit of the invention as claimed.

I claim:

1. A pump of the class described, the combination with an oil tubing string and an air pipe string, of a coupling secured to the lower end of the oil tubing, an internal seat in the coupling, a housing extending downwardly from the coupling, a spider secured to the lower end of the air pipe and engaging the seat, a tubular cylinder extending from the air pipe through the spider, a cylinder supporting member extending from the spider downwardly, a cylinder head at the lower end of the supporting member and having inlet and outlet check valves, a piston cylinder extending downwardly from the cylinder head, means forming a head in the lower end of the cylinder, a spring buffer in the head, a piston in the piston cylinder, a hollow stem extend-

ing upwardly from the piston slidingly through the first cylinder head and slidingly into the air pipe cylinder, there being air outlet ports through the hollow stem above the first cylinder head, and a hollow valve closed at its upper end and extending slidingly through the hollow stem and adapted to be reciprocated in the stem by engagement with the buffers as the piston goes up and down, there being ports and port closing means operated by the reciprocation of the valve so as to let the air from the air pipe raise the piston and so as to exhaust the air to lower the piston, there being means for conducting the exhaust air to the open well outside of the pump mechanism.

2. A pump of the class described, having an air pipe inside of an oil tubing, an air cylinder extending downwardly from the air pipe, a piston cylinder connected to the oil tubing and having an upper cylinder head and a lower cylinder head, a piston in the piston cylinder between the heads, a hollow stem extending from the piston slidingly through the upper head and slidingly into the air cylinder, a valve slidingly mounted through the hollow stem, intake and outlet check valves in the upper head, spring buffers for reciprocating the valve in the stem, there being ports and port closing means operated by the reciprocation of the valve for admitting air from the air pipe to the expansion chamber below the piston to raise the piston and for shutting off the air pipe pressure and exhausting the pressure from the expansion chamber to lower the piston, there being means for conducting the exhaust air to the open well outside of the pump mechanism.

3. A pump of the class described, a piston cylinder having an imperforate lower head and an upper head provided with intake and outlet check valves, a piston in the piston cylinder, an air pipe and means for leading the air from the air pipe to the expansion chamber below the piston and for admitting the air pressure to, and exhausting the air pressure from, the expansion chamber below the piston, there being means for conducting the exhaust air to the open well outside of the pump mechanism.

4. A pump of the class described, the combination with an oil tubing string and an air pump string, of a coupling secured to the lower end of the oil tubing, an internal seat in the coupling, a housing extending downwardly from the coupling and having exhaust ports, a spider secured to the lower end of the air pipe and engaging the seat, a tubular cylinder extending from the air pipe through the spider, a cylinder supporting member extending from the spider downwardly, a cylinder head at the lower end of the supporting member and having inlet check valves, a cylinder extending downwardly from the cylinder head, the cylinder

head extending outwardly from the cylinder to form an inlet oil chamber below the head between the cylinder and housing and an exhaust chamber above the cylinder head between the supporting member and housing, the inlet check valves leading from the inlet chamber below the cylinder head, and exhaust check valves in passages leading through the cylinder head and discharging into the exhaust chamber and ultimately to the ports in the housing and to the open well.

5. A pump of the class described, the combination with an oil tubing string and an air pump string, of a coupling secured to the lower end of the oil tubing, an internal seat in the coupling, a housing extending downwardly from the coupling and having exhaust ports, a spider secured to the lower end of the air pipe and engaging the seat, a tubular cylinder extending from the air pipe through the spider, a cylinder supporting member extending from the spider downwardly, a cylinder head at the lower end of the supporting member and having inlet check valves, a cylinder extending downwardly from the cylinder head, the cylinder head extending outwardly from the cylinder to form an inlet oil chamber below the head between the cylinder and housing and an exhaust chamber above the cylinder head between the supporting member and housing, the inlet check valves leading from the inlet chamber below the cylinder head, exhaust check valves in passages leading through the cylinder head and discharging into the exhaust chamber and ultimately to the ports in the housing and to the open well, a piston cylinder extending downwardly from the cylinder head, means forming a head in the lower end of the piston cylinder, a piston in the piston cylinder, a hollow stem extending upwardly from the piston slidingly through the cylinder head and slidingly into the tubular cylinder, there being outlet ports through the hollow stem above the cylinder head, and a hollow valve closed at its upper end and extending slidingly through the hollow stem and adapted to be reciprocated as the piston goes up and down, there being ports and port closing means operated by the reciprocation of the valve so as to let the air from the air pipe raise the piston and so as to exhaust the air past the check valves through the exhaust

ports in the cylinder head to the exhaust chamber and ultimately through the housing to the open well.

6. A pump of the class described, for lifting fluids from wells comprising a pump adapted to be lowered into an open well, means for supplying air under pressure to the pump, there being an exhaust passage leading from the pump, and a check valve controlling the flow through the exhaust passage, said exhaust passage discharging into the open well at a point above the inlet to the pump.

7. A pump of the class described, comprising a barrel, a piston reciprocable in the barrel, means providing well fluid inlet and outlet check valves to the barrel above the piston, means for intermittently supplying air pressure to the barrel below the piston, and means for alternately releasing the air pressure into the open well above the inlet check valves so as to produce reciprocation of the piston.

8. A pump of the class described, comprising a barrel having its lower end closed, a piston reciprocable therein, means for admitting well fluid to the barrel above the piston upon the downward stroke of the piston, means for discharging the fluid upwardly from the barrel upon the upward stroke of the piston, means for intermittently supplying air pressure to the barrel below the piston, and means for alternately releasing the air pressure through the barrel into the open well above the inlet to the barrel.

9. A pump of the class described, comprising a barrel having its lower end closed, a head within said barrel, inlet and outlet check valves mounted upon said head, an air cylinder, means for supplying air to said air cylinder, a piston reciprocable in said barrel below said head and having a hollow stem reciprocable in said air cylinder, means adapted to open and close said stem whereby said stem and piston may be forced downwardly by the air in said air cylinder or air may be admitted to said barrel below said piston, and means for discharging the air in said barrel which is below said piston into the open well.

In testimony whereof I have signed my name to this specification.

RALPH H. TUCKER.
